UNITED STATES PATENT OFFICE

WILBERT B. RASANSKY, OF MILWAUKEE, WISCONSIN

DISPLAY DEVICE

Application filed October 12, 1931. Serial No. 568,340.

The invention relates to display devices for containers such as boxes, crates, and baskets for fruits or vegetables, or other goods.

5 An object of the invention is to provide a cover-forming display device which can be readily applied to a goods container without the use of tools and which will retain the goods in the container while the 10 container is resting on its side in display position, the device being capable of repeated use and accommodating itself to variations in the size of the containers.

15 Another object of the invention is to provide a display device comprising a grille-like container cover having an elastic marginal band adapted to surround the edge portions of a container in tensioned frictionally engaged relation.

20 A further object of the invention is to provide a display device having grille-forming strips of elastic material, such as rubber, presenting display openings between them.

25 A further object is to provide a display cover which is constructed with smooth edges and corners, and which will form a guard for the rough and sharp edges and corners of the container, thus avoiding any 30 injury to the clothes and hands of attendants and customers in the store in which the container is displayed.

35 The invention further consists in the several features hereinafter set forth and more particularly defined by the annexed claims.

40 In the accompanying drawing, Fig. 1 is a perspective view of a display device constructed in accordance with the invention and adapted for use with a rectangular box or crate;

Fig. 2 is an end view partly in section of a container equipped with the display device of Fig. 1;

45 Fig. 3 is a perspective view of a modified form of display device adapted for use on a round container;

Fig. 4 is a side view of a round basket equipped with the display device in Fig. 3, and

50 Fig. 5 is a detail fragmentary sectional view of another modified form of display

device as it appears when applied to a container.

In the drawing, the numeral 10 designates an endless rectangular band or strap of flat elastic material, such as rubber. The opposite ends of the band 10 are connected by spaced parallel strips 11 of elastic material, such as rubber, forming a grille-like structure, and the opposite sides of the band may be connected by one or more similar cross strips 12. The band 10 and the strips 11 and 12 are preferably but not necessarily integrally connected, and in some instances the strips 11 and 12 may be elastic only along portions of their lengths and parts of the strips may be relatively rigid.

In the construction of Fig. 2, the display device of Fig. 1 is applied to a rectangular container 13 holding fruit or other goods. The device forms a cover for the open side of the container and the band 10 surrounds the marginal portions of the container adjacent its open side and frictionally engages the outer walls of the container under tension, thus retaining the device in position. The grille portion of the container prevents the fruit or other goods from falling out of the container when the container is set on its side in display position, and the openings in the display device permit the fruit or other goods to be effectively displayed. The elastic character of the strips 11 and 12 permits them to yield outwardly under the pressure of the fruit or other goods, and there are no sharp rigid corners which might cause bruising of the fruit. The tension on the grille-forming strips 11 and 12 may be adjusted by varying the position of the band with respect to the adjacent edge of the container.

The modified display device shown in Fig. 3 includes an endless circular band portion 110 of elastic material, such as rubber, connected by grille-forming strips 111 and 112 of elastic material which are connected thereto as in the device of Fig. 1. The device of Fig. 3 is adapted for use with a round-mouthed container, such as the conical basket 113 of Fig. 4. The band 110 of the circular device surrounds and friction-

ally engages the marginal portions of the basket, and the grille-forming strips 111 and 112 retain the fruit or other goods in the basket when it is rested on its side in display position.

The modified form of display device shown in Fig. 5 includes an endless elastic band 210 connected by grille-forming strips 211 and 212 of elastic material which at 10 their ends are flush with the edge of the band. When the device is applied to the container 13, the edge of the band 210 projects beyond the edges of the container so as to more fully cover any rough surfaces along 15 the edges of the container.

The display device of the invention can be quickly applied to a container by simply stretching the elastic marginal band over the container, the frictional engagement of the 20 band with the container serving to effectively hold the display device in place. Variations in the size of containers can be accommodated within limits because of the flexible character of the band. The device 25 can be used repeatedly and no tools are necessary for either applying or removing the device. The display device also forms a guard protecting the sharp and rough corners and edges of the container, so as to 30 avoid injury to the clothes and hands of attendants or customers in stores in which the containers are on display. The grille-forming elastic strips are under sufficient 35 tension to maintain them against lateral displacement in their plane, but they may be urged apart manually to permit the removal of articles from the container. After such 40 manual displacement these strips will spring back to their normal positions. The construction of the display device is such as to 45 avoid interference with stacking of the containers, or placing them side by side in close relation.

What I claim as new and desire to secure 50 by Letters Patent is:

1. A display device for a container, comprising a cover portion for said container through which articles therein may be viewed, and a flat elastic band connected to 55 said cover portion and adapted to surround and frictionally engage the container.

2. A display device for a container, comprising a flat elastic rubber grille-like cover portion, and an elastic rubber marginal container-engaging band connected to said cover portion.

3. A display device for a container, comprising a cover for said container through which articles therein may be viewed, and a flat elastic rubber band connected to said cover and adapted to surround and frictionally engage the container.

4. A display device for a container comprising a cover grille having elastic deformable parts yieldable outwardly by abutment

with articles in the container, and means for detachably securing said grille to the container.

5. A display device for a container comprising a cover grille having elastic rubber parts, and means for detachably securing 70 said grille to the container.

6. A one-piece display device for a container, comprising a cover grille and a marginal container engaging band integrally 75 connected and both formed of elastic rubber.

In testimony whereof, I affix my signature.

WILBERT B. RASANSKY.
